UNITED STATES PATENT OFFICE.

JOHN POWELL, OF KIDDERMINSTER, ENGLAND, ASSIGNOR TO HENRY JECKS
DIXON & SONS, OF SAME PLACE.

DESIGN FOR A CARPET-PATTERN.

Specification forming part of Design No. 6,094, dated August 27, 1872.

To all whom it may concern:

Be it known that I, JOHN POWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of this specification.

The design consists, mainly, of two shields—the one ornamented octagonally at the edge,

surrounded by a zigzag border, which is connected at one corner to the more curved border of the second shield. Alternating with these shields is an elongated figure, circular in the center, and connecting the borders of the first-named shields.

I claim as my invention—
The design for carpets, as shown.
JOHN POWELL.
